INVENTOR,
W. L. Bryan,
BY
E. W. Anderson,
His ATTORNEY.

UNITED STATES PATENT OFFICE.

WILLIAM L. BRYAN, OF SAN ANTONIO, TEXAS.

THILL-COUPING.

SPECIFICATION forming part of Letters Patent No. 448,499, dated March 17, 1891.

Application filed November 20, 1890. Serial No. 372,021. (No model.)

To all whom it may concern:

Be it known that I, WILLIAM L. BRYAN, a citizen of the United States, and a resident of San Antonio, in the county of Bexar and State 5 of Texas, have invented certain new and useful Improvements in Thill-Couplings; and I do declare the following to be a full, clear, and exact description of the invention, such as will enable others skilled in the art to which 10 it appertains to make and use the same, reference being had to the accompanying drawings, and to letters of reference marked thereon, which form a part of this specification.

15 Figure 1 of the drawings is a side elevation of my invention. Fig. 2 is a top plan view of same, and Figs. 3, 4, and 5 are detail views.

The invention relates to certain improvements in thill-couplings; and it consists in 20 the novel construction and combination of parts, all as hereinafter described.

In the accompanying drawings, the letter A represents the clip for securing the coupling to the axle. The upper portion of said 25 clip is bifurcated, as shown, and between the arms *a* of said portion is pivoted the contracted rear end of the arm or lever B. Said clip is also provided with the forward extensions or arms *b*, having each near its forward 30 end the shoulder *c*. At this point each of said arms is provided with a circular groove or recess *c'*, formed partly in the said shoulder and partly in the body portion of the arm. The apertures or surfaces of the said grooves 35 or recesses are of sufficient width to enable them to receive the ends *d* of the shaft-iron, for which they serve as seats. The ends of the shaft-irons being inserted in said grooves or seats, the lever-arm B is brought down- 40 wardly, the circular shoulders *e* of the bifurcated front portion of which engage, respectively, or bear against the upper surface of the ends of the shaft-iron, thus entirely inclosing them in their seats and effecting a 45 safe coupling. The lever-arm B is locked in this position by means of the spring-catches

F, which engage and retain the bifurcated forward or free end of said arm.

G is a spring interposed between the arms B and *b* for the purpose of normally holding 50 the arm B out of engagement with the shaft-iron, and consequently releasing said iron when the ends of said arm are released from the spring-catch.

It will be seen that if occasion requires by 55 the use of the coupling above described the shafts may be readily and quickly freed from the vehicle.

Anti-rattling devices H are provided in the 60 seats or recesses, as shown.

Having described the invention, what I claim as new, and desire to secure by Letters Patent, is—

1. The thill-coupling comprising the clip having the forward extensions or arms provided with the shoulders and the circular recesses for receiving the ends of the shaft-iron, and the bifurcated upper portion having pivoted therein the bifurcated lever-arm provided with the circular shoulders adapted to 65 engage the ends of the shaft-iron, the catch for locking said lever-arm in such engagement, and the spring interposed between said parts for retracting said arm when released, substantially as described. 70

2. In a thill-coupling, the combination, with the arms *b*, having each near its forward end a shoulder *c*, and a circular groove or recess *c'*, partially cut under said shoulder, of the pivoted bifurcated arm B, having the shoulders and the arc-shaped recesses, the spring- 75 catch for holding said parts in locked position, and the spring for retracting said arm B when the catch is released, substantially as specified. 80

In testimony whereof I affix my signature in presence of two witnesses.

WM. L. BRYAN.
